H. BADER

APPARATUS FOR MAKING THREADS AND THE LIKE OF ARTIFICIAL SILK

Filed March 5, 1926

FIG. 2.

Inventor:

Herbert Bader

By *June Janczak*
Attorney

UNITED STATES PATENT OFFICE.

HERBERT BADER, OF VIENNA, AUSTRIA.

APPARATUS FOR MAKING THREADS AND THE LIKE OF ARTIFICIAL SILK.

Application filed March 5, 1926, Serial No. 92,511, and in Czechoslovakia February 9, 1925.

In order to make a thread of the required quality out of artificial silk, various conditions must be fulfilled between the moment when the viscose issues from the spinneret and the moment when the filament enters the spinning vessel. In the first place the filament must remain in the precipitant until coagulation has been attained with sufficient thoroughness, because when centrifugal machines are used for winding the filament it is hardly possible to effect a second fixing without a second immersion. It is true that the length of filament immersed at one time in the precipitant can be extended to almost any desired degree if the filament is conducted over a filament-guide and then brought back again to the drawing roller but this involves two objections, namely that it causes the thread to kink and, moreover, almost the whole of the precipitant which the thread carries with it is scraped off. Both these circumstances are very detrimental to the quality of the silk, the first placing too great a mechanical strain upon the still exceedingly delicate filament, while the second prevents proper coagulation and smoothing of the thread owing to there not being a sufficient quantity of precipitant flowing back along it.

One or the other of the above-mentioned objections has been overcome in many cases. But the methods in question have hitherto never been employed in their entirety and in combination, which is the only way of insuring the production of a suitable filament, and the present invention consists in the construction of an apparatus in such manner as to fulfill all the above-mentioned requirements.

The drawings show a method of constructing the apparatus,

Fig. 1 being a side elevation, and

Fig. 2 a plan view.

An essential feature of the invention is that the filament drawing roller 1 is positioned in such a manner that a downwardly-extending line tangent to its circumference at one end of its horizontal diameter will be perpendicular, or nearly perpendicular, to the outlet orifice of the spinneret 2, while a similar tangent at the opposite end of said

diameter will be perpendicular, or nearly so, to the center of the spinning vessel 3.

The advantage of this arrangement is, on the one hand, that the filament 4 is brought to the drawing roller without kinking and, at the same time, that until the filament reaches the roller precipitating-fluid flows along it continually, because that portion of the fluid which passes back into the bath from the filament is bound to flow along the latter, whereas in the case of a filament which is drawn out of the bath obliquely, a great proportion of the precipitant is bound to drip off from the thread under gravity and is thus no longer available for coagulation. Further, the filament running off the drawing roller falls in the present construction perpendicularly into the centre of the receiving device of the spinning vessel, which is absolutely necessary to insure its being properly introduced into said device.

Moreover, the drawing roller 1 is beveled along towards the edges of its periphery in such a manner that any filament which may have become wound on the roller can easily be stripped off laterally.

I claim as my invention:

1. Apparatus for making threads of artificial silk, comprising a tank to contain a precipitant, a spinning vessel at one side thereof, a spinneret submerged in the precipitant in said tank with its outlet orifice directed upwardly, and a drawing roller located above the tank and spinning vessel in such a position that a downwardly-extending line tangent to the circumference of the roller at one end of its horizontal diameter will pass perpendicularly through the outlet orifice of the spinneret while a similar tangent at the opposite end of said diameter will pass perpendicularly through the center of the spinning vessel.

2. Apparatus according to claim 1, in which the drawing roller is beveled along both edges of its periphery to enable a filament wound thereon to be stripped off laterally from the roller.

In testimony whereof I affix my signature.

HERBERT BADER.
